UNITED STATES PATENT OFFICE

CHARLES WILFRED PALMER AND WILLIAM WHITEHEAD, OF SPONDON, NEAR DERBY, ENGLAND, ASSIGNORS TO CELANESE CORPORATION OF AMERICA, A CORPORATION OF DELAWARE

PROCESS AND APPARATUS FOR THE MANUFACTURE OF ARTIFICIAL SILK AND LIKE THREADS

Application filed January 29, 1923, Serial No. 615,682, and in Great Britain February 18, 1922.

This invention relates to new or improved process and apparatus for the manufacture of artificial silk and like threads by processes wherein solutions of cellulose acetate, nitro-cellulose, ethyl, methyl or benzyl cellulose or other cellulose esters, ethers or derivatives of cellulose in or containing volatile or vaporizable solvents or liquids, are extruded into the air or a gaseous atmosphere, the filaments being solidified by evaporation of the solvents or liquids after issuing from the jets or nozzles, the resulting filaments, being associated as threads, and being led or fed to bobbins or other winding devices on which they are continuously wound up. Usually in such processes the air or other gaseous atmosphere in which the filaments are extruded is heated.

In the manufacture of artificial threads by such processes, hereinafter referred to as dry spinning or evaporative processes, the usual procedure is to wind the thread consisting of a number of filaments on to the bobbin or other winding device without twisting, and subsequently to twist the thread in a separate operation on another machine.

The surprising discovery has now been made that winding and twisting of the thread can be effected simply and economically as a single operation, by applying cap twisting and winding, hereinafter shortly referred to as cap spinning, to the travelling thread of associated filaments.

Any suitable form or arrangement of cap spinning device may be employed, the travelling thread being led or fed to a point vertically above the spindle of the cap spinning device and thence passing under the lower edge of the cap on to the bobbin, spool, tube or the like of the cap spinning device, on which it is wound.

The bobbin, spool, tube or the like will be rotated at a higher speed than that at which the thread is fed to it, and it will be understood that the thread, passing from a point above the spindle down round the bottom of the cap on to the bobbin or the like, will receive a twist and that the bottom of the cap, while guiding the thread on to the bobbin or the like allows the thread to rotate about the

axis of the spindle and bobbin or the like. The amount of twist imparted to the thread depends upon the difference between the speed of feed of the thread and the speed of the bobbin or winding device.

Preferably the cap and spindle are stationary while the bobbin, spool, tube or the like is rotated at the required speed, but the cap or the cap and spindle might rotate also.

A feed roller, drawing roller, godet or any other suitable means may be employed for feeding the thread of associated filaments to the cap spinning device at the required speed.

The amount of twist imparted to the thread may be varied by varying the speed at which the thread is fed to the cap spinning device, or by varying the speed of rotation of the bobbin, spool, tube or the like of the cap spinning device, or by both means, or in any other suitable way.

The thread may be traversed on the bobbin, spool, tube or the like by any known or suitable means, as by traversing the bobbin or the like vertically relatively to the cap, or by traversing the cap vertically relatively to the bobbin or the like.

The thread may be traversed in various ways by any known or suitable means so as to give a parallel wind, spool wind, bottle bobbin wind or any other desired kind of wind.

Any desired number of the cap spinning devices may be employed in combination or association with a metier or apparatus for producing artificial threads by the dry spinning, or evaporative method, according to the number of jets or nozzles comprised therein or to the number of threads produced thereby or other requirement.

The cap spinning devices are preferably situated outside the metier or spinning apparatus when this is of the enclosed type, but they may be situated inside if desired.

A feed roller, drawing roller, godet or other suitable device or a row or line of such rollers or devices may serve to feed the threads to any desired number of cap spinning devices disposed in one or more rows or lines, or otherwise as desired. Such feed device or devices will feed the threads at a speed less than the

55

60

65

70

85

90

95

100

surface speed of the bobbins or other winding members of the cap spinning devices, and preferably at a greater speed than that of the extrusion of the filaments, so that these are extended in their transit to the cap spinning devices.

In twisting and winding threads of associated filaments by means of cap spinning devices as hereinbefore referred to, the bobbins, 10 spools, tubes or the like may be driven at any desired or suitable speeds relatively to the speed of feed of the threads to them. Usually they will be driven at much higher circumferential speeds than the speed of feed of the thread. For example the speed of the bobbins 15 or the like may be about 7,000 to 10,000 revolutions per minute or more. We do not of course in any way limit ourselves to this, as they may be run at lower or higher speeds, or much higher speeds, even 20,000 R. P. M. or more.

For cap twisting and winding threads of associated filaments of cellulose acetate or other cellulose derivatives contemporaneously with their production by evaporative processes, it is of great advantage to lubricate 25 the filaments or threads on their way to the cap spinning devices. This may be effected in any suitable way, for instance, by applying oil or other lubricating liquids thereto in a manner analogous to those sometimes practised in spinning or other textile operations, for example by causing the threads of associated filaments on their way to the cap spinning devices to pass over surfaces supplied or 30 impregnated with the oil or lubricating 35 liquid.

It is likewise of advantage to damp or moisten the filaments or threads on their way to the cap spinning devices. This may be effected by any suitable means, for example by 40 exposing the travelling filaments or threads to humidified air, or passage over a wetted roller or other damp surface on their way to the cap spinning devices.

When artificial silk or the like is twisted 45 and wound in the manner hereinbefore described the thread is subject to tension. This tension can be modified in various ways, so as to be less than or greater than the elastic 50 load of the thread, e. g. by regulating the height of the upper thread guide relatively to the lower edge of the cap, or by suitably adapting the diameter of the cap at the base, in relation to the diameter of the bobbin 55 barrel, tube or the like, or by lubricating or wetting the thread, on its way to the cap spinning devices, or by adjusting the amount of surface contact between the thread and the cap edge, or in any other suitable way.

If required the thread may be extended 60 during twisting, by increasing the tension of winding, or by damping the thread on its way to the cap spinning devices, or in any other desired way.

It is also to be understood that in the case

of filaments dry-spun from solutions of nitrocellulose or like flammable cellulose derivatives, where it is sometimes the practice to wet or damp the filaments or threads with water or the like for safety's sake on their way to winding up, the filaments or threads may be damped or wetted in their travel to the cap spinning devices.

The invention may be applied with advantage in dry spinning processes wherein the threads of artificial silk or the like are spun downwards in the metier and the travelling threads of associated filaments, solidified therein by evaporation of solvent, are led out and wound continuously by mechanism outside the metier, as described and claimed in the U. S. Patent to Roy 1,602,125, October 5, 1926, the cap spinning mechanism serving simultaneously to twist and wind the threads fed from the metier.

The invention may, however, be applied to dry spinning metiers or apparatus in which the threads are spun upwards or otherwise. Also, as before mentioned, the cap twisting and winding devices may be situated inside or outside the metiers or machines in any desired way.

In the case of dry spinning processes in particular, the cap spinning process worked in conjunction with the extruding process, 95 enables at least one operation to be cut out as compared with the previous method of winding the threads of associated filaments and afterwards twisting the threads in a separate operation.

The possibility of winding in special manners, such as bottle bobbin winding, in the cap spinning process is a further advantage in that rewinding of the twisted artificial silk on to bottle bobbins for knitting purposes can 105 be avoided.

A further advantage is that the artificial silk or the like is handled much less by the cap spinning process than by the process of winding and twisting the threads of associated filaments by separate processes or operations.

It is to be understood that the invention includes both processes and apparatus wherein cap spinning is applied in combination with 115 any processes of producing artificial silk, artificial wool, or other artificial threads or filaments from solutions of cellulose derivatives by dry spinning or evaporative methods.

The accompanying drawings show one 120 form of apparatus constructed in accordance with the invention, as applied to the manufacture of artificial silk from solutions of cellulose acetate or other cellulosic derivatives by the method described in the said U. S. Patent 1,602,125, that is to say where- 125 in the filaments are spun downwards into an evaporative atmosphere in an enclosed cas- ing, the travelling threads of associated fila- 130 ments, solidified therein by evaporation of

solvent, being led out of the casing and wound up continuously by mechanism outside the same. It is to be understood, however, that the particular form of apparatus illustrated is given only by way of example and that the invention is in no way limited thereto, being capable of wide modification within the spirit of the invention.

Fig. 1 is a diagrammatic front elevation of a portion of a spinning cabinet or metier with the cap spinning devices appertaining thereto.

Fig. 2 is a diagrammatic side elevation of the metier and cap spinning apparatus, with the side of the metier removed.

Fig. 3 is a detail sectional elevation taken on line 3-3 Fig. 1, showing one of the cap spindles with its bobbin and bobbin carrier.

Figs. 4 and 5 are a side elevation and a plan of one of the upper thread guides.

1 indicates the enclosing casing of the spinning metier, divided up by vertical partitions 1^a into any number of relatively narrow vertical compartments 1^b in the upper part of 25 which are located the jets 2 from the orifices of which the filaments are discharged down into a current of air admitted below and which rises round the steam pipes 3^a and baffles 3^b of an air heater 3, the hot air carrying the solvent vapours evolved from the filaments passing away from the top of the casing, and the threads 4 of associated filaments being led round a guide 5 and out through small orifices in front of the metier casing, 35 all as described in the said U. S. Patent 1,602,125. Each compartment contains only a small number of jets, two are shown, but one might be employed in each cell or more than two in each cell. 6 indicates one of a line of waste rollers mounted below the jets 40 and extending across the metier and driven frictionally by a line of discs or rollers 6^a as stated in the said patent, said waste rollers serving for catching and winding up the filaments or breakage or during interruption of 45 their winding.

7 represents a line of godets or feed rollers all fast on a shaft 8 extending the width of the metier and mounted in bearings in brackets 9 bolted on the side frames, one of which is seen at F Fig. 2 and on the intermediate frames F¹ of the cap spinning apparatus. The series of feed rollers are driven at a surface speed greater than the speed of 55 extrusion of the filaments (so as to draw out or extend the threads), by a gear wheel 10 on the end of shaft 8, meshing with a gear wheel 11 on a countershaft mounted parallel to shaft 8 and receiving the drive by a chain 12 from a chain wheel 12^a on the end of the shaft 13 of the main drum 14 that drives the bobbins.

15, 15 indicate a row of back guide hooks carried by a horizontal bar 16 extending the width of the metier and supported by

brackets 17 on the side frames F and on each of the intermediate frames F¹.

18 is a fixed spindle rail extending the width of the metier, and carrying the fixed spindles 19, 19 . . . on each of which is mounted a loose cap 20. 21 is a traversing rail on which are mounted a corresponding series of bobbin carriers 22, Fig. 3, formed with driving whorls 22^a, tubes 22^b and projections or shoulders 22^c to engage the bobbins 23, the fixed spindles 19 passing up through the bobbin carriers and their tubes, so that the bobbins are driven by the bobbin carriers and can be traversed up and down by the rail 21, while the spindles remain stationary.

The fixed rail 18 is supported from each intermediate frame F¹ by an arm 24 bolted to the frame as at 24^a so as to be vertically adjustable in height on a gib or guide 26 for levelling the rail 18, which is also supported at its ends by arms or supports mounted on the side frames F. A lower horizontal fixed guide bar 27 extending the width of the metier is similarly adjustably mounted at each intermediate frame F on an arm 28 and on the end frames F.

The traversing rail 21 is carried on vertical pokers 29 reciprocating through and guided in holes in the fixed rail 18 and the lower guide bar 27, and attached at bottom to the chains 30 that impart the traversing motion to the pokers, these chains being fixed to the horizontal traversing rod 31 and passing over guide pulleys 32 carried on a line of horizontal frame bars 33 (Figs. 1 and 2), so that the traversing motion is imparted to the pokers 29 and rail 21. The horizontal traversing rod 31 can be reciprocated by any known mechanism, not shown.

The drum 14 (or a line of such drums) for driving the bobbin carriers extends the width of the metier, its shaft 13 being mounted in a bracket 34 in each side frame, and can be driven by any convenient means.

In the arrangement shown, each pair of adjacent bobbin carriers is driven by an endless strap 35 passing round the whorls of both. Each strap 35 runs from the drum 14 forwards up round a skew jockey or tension pulley 36 situated behind the space between the two adjacent spindles, thence back round a rear jockey or tension pulley 37 (Fig. 2), then forward and around the whorls 22^c of the two bobbin carriers, and thence returning to the drum 14. The series of front jockey pulleys are mounted in forks 38 bolted at the requisite skew angle to rocking levers 39 mounted on a horizontal rod 40 mounted in the intermediate and side frames, the rocking levers being each counter-weighted as indicated in Fig. 2. The rear jockey pulleys 37 are mounted behind the front jockey pulleys 36 in arms or brackets 42 adjustably mounted on a horizontal rod 43

mounted in the side frames F and intermediate frames F^1 parallel with the rod 40.

A row of thread guides 44 with eyes 44^a, shown in detail on Figs. 4 and 5, are mounted directly above the corresponding spindles on a line of horizontal bars 45 mounted on the intermediate and side frames and adjustable in height by any suitable means. The thread guides 44 are hinged as at 46 to allow of being swung up for removal and replacing of the caps and bobbins.

47 represents a line of front waste rollers mounted with slight friction on a shaft 48 in bearings in the side and intermediate frames and extending the width of the metier below and in front of the line of godet rollers 7, so that when a thread is broken between the godet and the bobbin on changing the bobbin or otherwise, the broken 10 thread is caught and wound up on the waste rollers 47. The shaft 48 of these rollers is driven from the godet shaft 8 by a chain 49 passing round chain wheels on the shafts 8 and 48 and round a tension pulley 50.

The threads 4 of the associated filaments led out of the metier casing as explained are passed forwards over the godet roller 7, then back under this roller at an angle up through the back guide hooks 15, thence up again 20 over the godet roller 7 and forwards down through the eyes 44^a of the thread guides 44 and under the bottom of the caps 20 on to the bobbins which are rotated at a high speed, for example 10,000 R. P. M. or more by the 30 straps 35, the bobbins at the same time being raised and lowered by the traversing mechanism to wind the thread evenly thereon, whilst the spindles 19 and the caps 20 mounted loose thereon remain stationary.

As the peripheral speed of the bobbin is greater than the speed at which the thread is fed to it by the godet roller, the thread is correspondingly rotated and twisted simultaneously with the winding, the bottom of 40 the cap guiding it on to the revolving bobbin and imparting a drag to it, thus enabling it to be wound on to the bobbin. The thread at the same time is permitted to rotate about the axis of the spindle and bobbin, the amount of twist depending upon the difference between the speed of the feed of the 50 thread and the peripheral speed of the bobbin.

When a given bobbin has been fully wound it can be stopped by the attendant's hand 55 and removed by swinging up the thread guide, taking off the cap and sliding off the spindle and a fresh bobbin can then be put on to the spindle.

The amount of twist imparted to the thread 60 can be varied by varying the speed of the godet roller or of the bobbins, or the speed of both, or otherwise as desired.

The tension of the thread may be varied by adjusting the height of the thread guides 65 44, or by employing caps of other diameter,

or damping the threads, or in any other way.

It is desirable, as before mentioned, to lubricate the filaments with oil or other lubricating liquid, on their way to the cap spinning devices. This can be done in any appropriate way, for example by leading them over a pad, roller or other surface supplied or impregnated with the lubricating liquid and disposed between the metier and the drawing rollers 7. Likewise if it is desired to damp the filaments on their way to the cap spinning devices this can be done in any convenient way, for example by humidifying the air in the room, or by discharging humidified air on to the threads of associated filaments, or causing them to pass over a damp roller or other surface, in their travel between the metier and the drawing roller or the cap spinning devices.

Further, it will be understood that instead of bobbins one may employ tubes or any other desired winding devices for the threads, and that any known or suitable traversing mechanism may be employed according to the type of wind desired, for example a parallel wind, 80 spool wind, bottle bobbin wind or other desired form of wind.

Also instead of traversing the bobbins or the like while the cap and spindle remain stationary, the spindle and cap may be traversed up and down through the bobbin or the like while this only revolves without traversing up and down.

What we claim and desire to secure by Letters Patent is:—

1. A process for the continuous production from solutions of cellulose acetate or other substitution derivative of cellulose, of packages of twisted artificial threads wound on winding members, comprising forming continuous filaments by extrusion of the solution into a gaseous atmosphere, solidifying the filaments by evaporation of the solvent in said gaseous atmosphere, associating the filaments, leading the associated filaments towards the winding member from a point substantially in alignment with the axis of the winding member, deflecting the associated filaments inwards on to the winding member over an annular surface co-axial therewith, and rotating the winding member at a higher surface speed than the linear speed of travel of the filaments, thereby twisting the associated filaments and winding them as a twisted thread on to the winding member.

2. A process for the continuous production from solutions of cellulose acetate or other substitution derivative of cellulose, of packages of twisted artificial threads wound on winding members, comprising forming continuous filaments by extrusion of the solution into a sealed gaseous atmosphere, solidifying the filaments by evaporation of the solvent in said sealed gaseous atmosphere, leading the filaments out of the sealed gaseous

- atmosphere in association, leading the associated filaments towards the winding member from a point substantially in alignment with the axis of the winding member, deflecting the associated filaments inwards on to the winding member by an annular surface coaxial therewith, and rotating the winding member at a higher surface speed than the linear speed of travel of the filaments, thereby twisting the associated filaments and winding the twisting thread on to the winding member. 5
3. A process according to claim 1, characterized in that the filaments are lubricated with lubricating liquid before they are subjected to the twisting and winding operation. 15
4. A process according to claim 1, characterized in that the filaments are treated with a humidifying agency before they are subjected to the twisting and winding operation. 20
5. A process according to claim 1, wherein the filaments are formed by extruding the solution downwards into an upwardly flowing gaseous atmosphere. 25
6. A process according to claim 1, wherein the filaments are led to the winding member at a greater linear speed than that of extrusion, so that they are extended before they are twisted and wound. 30
7. Apparatus for the manufacture of artificial threads from solutions of cellulose acetate or other substitution derivatives of cellulose, comprising, in combination, jets through which the solution is extruded to form filaments, means for solidifying the filaments by evaporation of the solvent in a gaseous atmosphere, means for associating the filaments into threads, and cap spinning devices for simultaneously twisting and winding the threads. 35
8. Apparatus for the manufacture of artificial threads from solutions of cellulose acetate or other cellulose derivatives by the evaporative method, comprising in combination an inclosed metier casing, means in association with the same for maintaining a flow of air therethrough, jets disposed in the casing for extruding the solution as filaments therein, cap spinning devices located outside the metier casing, means permitting of conveying the filaments, in association for threads, out of the casing to points above the cap spinning devices and thence to the cap spinning devices and means for driving the winding members of the cap spinning devices at a higher circumferential speed than the speed of travel of the associated filaments thereto, whereby the associated filaments are simultaneously twisted and wound as produced. 45
- 50
- 55
- 60
- 65
9. Apparatus for the manufacture of artificial threads from solutions of cellulose acetate or other cellulose derivatives by the evaporative method, comprising in combination jets whereby the solution is extruded to form filaments, means for solidifying the filaments by evaporation of the solvent in a gaseous atmosphere, cap spinning devices to which the filaments are conveyed in association for threads, means for conveying the associated filaments to said cap spinning devices, the winding members of the cap spinning devices being adapted for driving at a circumferential speed greater than the speed of travel of the associated filaments thereto, and means for lubricating the filaments in their travel to the cap spinning devices. 70
10. Apparatus for the manufacture of artificial threads from solutions of cellulose acetate or other cellulose derivatives by the evaporative method, comprising in combination jets whereby the solution is extruded to form filaments, means for solidifying the filaments by evaporation of the solvent in a gaseous atmosphere, cap spinning devices to which the filaments are conveyed in association for threads, means for conveying the associated filaments to said cap spinning devices, the winding members of the cap spinning devices being adapted for driving at a circumferential speed greater than the speed of travel of the associated filaments thereto, and means for humidifying the filaments in their travel to the cap spinning devices. 75
11. Apparatus for the manufacture of artificial threads from solutions of cellulose acetate or other cellulose derivatives by the evaporative method, comprising in combination an enclosed metier casing, means for maintaining an upward flow of air therethrough, jets situated in the upper part of said casing and arranged to discharge the filaments downwards into the upwardly flowing air, cap spinning devices located outside the metier casing, means permitting of conveying the filaments, in association for threads, out of the casing to points above the cap spinning devices and thence to the cap spinning devices, and means for driving the winding members of the cap spinning devices at a higher circumferential speed than the speed of travel of the associated filaments thereto whereby the associated evaporatively produced filaments are simultaneously twisted and wound as produced. 80
12. Apparatus for the manufacture of artificial threads from solutions of cellulose acetate or other cellulose derivatives by the evaporative method, comprising in combination an enclosed metier casing, means for maintaining an upward flow of air therethrough, jets situated in the upper part of said casing and arranged to discharge the filaments downwards therein, cap spinning devices located outside the metier casing, means for leading the evaporatively produced filaments, in association for threads, out of 85
- 90
- 95
- 100
- 105
- 110
- 115
- 120
- 125

said casing, a driven drawing and feeding roller for feeding the threads of associated filaments to the cap spinning devices, and a driven waste roller located under the path of the associated filaments between the cap spinning devices and said drawing and feeding roller.

13. Apparatus for the manufacture of artificial threads from solutions of cellulose acetate or other cellulose derivatives by the evaporative method, comprising in combination an enclosed metier casing, means for maintaining an upward flow of air therethrough, jets situated in the upper part of said casing and arranged to discharge the filaments downward therein, cap spinning devices located outside the metier casing, means for leading the evaporatively produced filaments, in association for threads, out of said casing, a driven drawing and feeding roller for feeding the threads of associated filaments to the cap spinning devices, a line of front guides for the threads, located over the vertical axes of the caps, and a line of back thread guides mounted behind said feed roller, substantially as described.

14. A process for the continuous production from solutions of cellulose acetate or other substitution derivative of cellulose, of packages of twisted artificial threads wound on winding members, comprising forming continuous filaments by extrusion of the solution into a gaseous atmosphere, solidifying the filaments by evaporation of the solvent in said gaseous atmosphere, associating the filaments, leading the associated filaments to the winding member from a point substantially in alinement with the axis of the winding member, rotating the winding member at a higher surface speed than the linear speed of travel of the filaments to twist the associated filaments into thread, and continuously imparting a drag to the thread at points constituting a circle in a plane at right angles to the axis of the spindle to wind the twisted thread on to the winding member.

15. Apparatus for the continuous production from solutions of cellulose acetate or other substitution derivative of cellulose, of packages of twisted artificial threads wound on winding members, comprising, in combination, jets through which the solution is extruded to form filaments, means for solidifying the filament by evaporation of the solvent in a gaseous atmosphere, means for associating the filaments, a spindle, a cap mounted on the spindle and having a smooth edge, a thread guide substantially in alinement with the said spindle, a winding device rotatably mounted on said spindle, and means for driving said winding device at a combined twisting and winding speed, the arrangement being such that the associated filaments pass downward from the thread guide and inwards over the edge of the cap to the winding device, the

filaments being twisted into thread by the rotation of the winding device and the thread being wound on to the winding device by the drag imparted to it, during its passage over the edge of the cap.

In testimony whereof we have hereunto subscribed our names.
